UNITED STATES PATENT OFFICE.

THOMAS B. JEFFERY, OF CHICAGO, ILLINOIS.

VELOCIPED.

SPECIFICATION forming part of Letters Patent No. 449,220, dated March 31, 1891.

Application filed May 6, 1890. Serial No. 350,807. (No model.)

To all whom it may concern:

Be it known that I, THOMAS B. JEFFERY, a citizen of the United States, residing at Chicago, county of Cook, and State of Illinois, 5 have invented certain new and useful Improvements in Velocipede Dress-Guards, which are fully set forth in the following specification, reference being had to the accompanying drawings, forming a part thereof.

10 In the drawings, Figure 1 is a side elevation of a drive-wheel of a Safety bicycle with the adjacent portion of the frame and driving-gear and having devices which constitute my improved dress-guard applied thereto. Fig. 2 is a section at the line 2 2 through the mud-guard-supporting fork and mud-guard and lateral dress-guard. Fig. 3 is a section at the line 3 3 through the fork, showing the means of supporting the chain dress-guard. 20 Fig. 4 is a detail plan of a portion of a jointed frame containing the pivot of the two parts.

This invention relates to improvements in the dress-guard which is designed to protect the dress of the rider from the mud carried 25 by the drive-wheel, and also to improvements in the guard which covers the drive-chain, and is designed to prevent the entanglement of the dress of the rider therewith. The first-mentioned guard has heretofore generally 30 been made either of wire-cloth or rods secured to the mud-guard or fork or chain-guard or other essential parts of the framework, or in some instances to special parts added permanently to the frame-work as 35 means of securing such wire-cloth. The present invention is designed to provide a guard made of wire-cloth or similar material, which shall be complete within itself independently of its fastening to the machine, and adapted 40 to be removably secured, so that when the machine is used by a man, who has no need for the dress-guard, he can remove the same without mutilating or practically unconstructing it. It comprises, therefore, two independent 45 guards A A, each made of a piece of wire-cloth bound by a rigid metal frame B, which, as illustrated, is of rod bent in the proper shape and having the several wires of the wire-cloth fastened at their ends, which con- 50 stitute the margin of the cloth, permanently to such frame wire or rod. The entire guard

thus constructed is secured to the fork C, being the fork which is primarily intended to uphold the mud-guard D, by means of staple-bolts or hooked bolts E—that is, bolts having 55 a hook E' at one end adapted to hook around the frame-rod B, while the other end or stem of the bolt passes through a hole in the fork C and is drawn tight, its hook E' being clamped onto the frame-rod and the latter 60 drawn firmly against the inner side of the fork by means of the nuts E² applied on the outer ends of the bolts.

The other portion of the dress-guard—to wit, that which guards the dress from the 65 chain—is represented by F. This chain dress-guard is secured at one end by a lug extending from it up to one of the bolts E, which serves to fasten the dress-guard A in place on the fork C. The guard F extends from 70 this point of support along over the chain and around the sprocket-wheel G to the lower side thereof, where it terminates, so far as the portion which covers the chain is concerned; but it has the extension F' in the form of a 75 rod bent in a vertical plane outside of the plane of the sprocket-wheel—that is, substantially in the plane of the outer edge of the chain-guard F—extending around the remainder of the sprocket-wheel not shielded 80 by the curved portion of the guard F and fastened at its upper end to said guard. This extension F', in addition to supplementing the guard F as a means for keeping the dress of the rider off the wheel, serves as a means 85 of affording a second support for the guard F. It is made rigid at both ends with the guard F, and where it passes by the fork C' a post H, rigidly fastened to said fork, juts out horizontally and has an eye at its outer 90 end through which the rod F' passes, and at which said rod is rigidly secured to the post, thus forming the second support for the entire guard F F', and holding it rigidly in place without the necessity of securing it to 95 any other portion of the frame than the two forks or two portions of the fork, for they are made integral—to wit, C and C'. This or any equivalent mode of securing the chain dress-guard in such manner that it is supported upon the parts which may be called 100 the "frame" of the wheel driven by the

chain, said frame, as herein shown, consisting of the forks mentioned, is of especial importance in machines in which the frame of the driving-wheel is pivotally connected to the remainder of the frame (represented in the drawings by the frame-arm H) by a horizontal pivot permitting said two parts of the frame to move vertically independently of each other, because such movement of the frame, (represented by the arms H'), if the dress-guard F were connected to that part of the frame, would throw it out of proper relation to the chain and either prevent it from suitably guarding the chain or throw it onto the latter as the frame H moved relatively to the frame of the drive-wheel, and it is in order to adapt such chain dress-guard to such machines that I have devised the above-described mode for supporting it wholly upon the frame of the wheel driven by the chain.

I claim—

1. In a velocipede having the frame of the driving-wheel pivotally connected to the remainder of the frame at a horizontal pivot, whereby said two parts may have vertical movement independently of each other, in combination with the drive-wheel frame and the drive-wheel journaled therein, the crank-shaft and the sprocket-wheels on said crank-shaft and drive-wheel shaft, respectively, the chain which communicates power between them, and the chain dress-guard F, overhanging said chain supported by connection solely with the drive-wheel frame, substantially as set forth.
2. In a velocipede, in combination with a drive-wheel, the crank-shaft, and the fork which connects said shaft to the drive-wheel axle, the sprocket-wheels on said crank-shaft and drive-wheel shaft, respectively, and the chain which communicates power between them, the dress-guard over such chain ex-

tending partly around the driving sprocket-wheel and having the extension F', consisting of a rod rigid with said dress-guard above and below said sprocket-wheel, and a post extending from said fork at the side of the driving sprocket-wheel toward the drive-wheel axle and rigidly connected to said extension F', whereby said fork supports the chain dress-guard, substantially as set forth.

3. In a velocipede, in combination with the fork which extends from the crank-shaft to the drive-wheel shaft and the fork which upholds the mud-guard, the sprocket-wheels on said shafts, respectively, and the chain which communicates power between them, the chain dress-guard F, overhanging said chain and extending half-way around the driving sprocket-wheel and secured at one end to the fork which upholds the mud-guard and at the other end having the extension F', consisting of a rod rigid with said chain-wheel guard and extending outside of the vertical plane of the driving sprocket-wheel around the portion of said wheel not covered by the guard F, and the post H, jutting horizontally from the fork and secured to said extension F', substantially as set forth.

4. In a velocipede, in combination with the forks C and C', the removable dress-guards A B and the bolts which secure them to the fork C, and the chain dress-guard F, having its upper end secured to the fork C by one of the bolts which fastens the dress-guard A B to said fork, substantially as set forth.

In testimony whereof I have hereunto set my hand, in the presence of two witnesses, at Chicago, Illinois, this 1st day of May, 1890.

THOS. B. JEFFERY.
